UNITED STATES PATENT OFFICE.

ROBERT DIAMOND MAYO, OF CLEVELAND, OHIO, ASSIGNOR OF ONE-HALF TO ELMER E. SLYFIELD, OF FRANKFORT, MICHIGAN.

SANITARY CLOSET-SEAT.

1,050,283.

Specification of Letters Patent. Patented Jan. 14, 1913.

Application filed April 10, 1912. Serial No. 689,937.

To all whom it may concern:

Be it known that I, ROBERT DIAMOND MAYO, a citizen of the United States, residing at Cleveland, Cuyahoga county, Ohio, 5 have invented certain new and useful Improvements in Sanitary Closet-Seats, of which the following is a specification, which, together with the accompanying drawings, will clearly explain to those skilled in the 10 art to which it pertains the nature of the invention.

This invention relates to seats for toilet closets, and its principal object is to provide means whereby such seats can be sterilized, 15 for sanitary purposes, to prevent the transmission of disease from one user to another.

It consists, in its now preferable form, of a double faced seat, with means whereby it can be reversed by being turned over; and 20 further means whereby that side which lies undermost is in close relation to a body of sterilizing substance, preferably a suitable fluid which is sufficiently volatile in its nature to emit a vapor or gas capable of carrying 25 the sterilizing qualities of the fluid to and against that surface of the seat that is directly exposed to it; and it further consists in such improvements of contributary details as will hereinafter be set forth.

30 The accompanying drawings show the invention in forms and proportions that are now considered most desirable, but, obviously, some of the parts shown may be used without others, or in connection with new 35 devices of future development, and still be within the scope of the claims.

Figure 1 is a top plan view of a closet bowl particularly adapted for use with this invention. Fig. 2 is a top plan view of a 40 seat made in accordance with the invention and applied to the form of bowl shown in Fig. 1. Fig. 3 is a vertical longitudinal section of the same on the line 3, 3 of Fig. 2. Fig. 4 is an enlarged cross section of portions 45 of the rim of the bowl and of the seat, the section being taken on the line 4, 4 of Fig. 2. Fig. 5 is a detached view of a metallic ring used in the construction of the seat, the outlines of the wooden seat-sections 50 being shown by dotted lines. Fig. 6 is a vertical longitudinal section of a short portion along the seat and the rim of the bowl, the section being taken on the line 6, 6 of Fig. 2, in the vicinity of one of the 55 partitions or cross walls in the groove of the

bowl. Fig. 7 illustrates a modification of the means for pivotally mounting the seat, allowing of its being turned over either side-wise as in Fig. 1, or endwise, as desired. Fig. 8 is a detached view of one of the side-pivot bolts of the structure shown in Fig. 7.

As embodied in the drawings a toilet-closet bowl A, of any desired shape, has a groove a around the entire upper edge of the opening. At suitable intervals this groove 65 may be crossed by partition walls a^1 which divide the groove into sections which may be closed or which may be communicating through apertures a^5 , (see Figs. 4 and 6) so that liquid poured into any section will 70 flow into and charge the other sections. The bowl, as shown, has a rearward extension A^1 , formed integral with it, to afford support for the seat and cover hinges.

The seat B is double faced, that is with 75 usable faces b on both sides, these faces being made of wood in accordance with general practice. They are of such size and shape in cross section that they will fairly fit in the groove in the top of the bowl but 80 will not extend into its full depth. In order to strengthen and support the seat its two wooden faces are secured upon the opposite sides of a sheet metal ring C, which follows the general contour of the seat form.

The wooden faces of the seat are preferably made in sections, (four being shown in the drawings but a greater or less number may be used as found desirable) with spaces b^1 between their ends, these spaces being 90 designed to fit over the partitions a^1 in the grooves in such manner that the metal ring C rests upon the top surfaces of the partitions and supports the seat.

The metal ring is wider than the wooden seat sections, projecting beyond their outer edges c^2 and resting upon the flat top of the outer rim a^2 in the grooved bowl, while at the inner edges c^3 , the seat sections have beveled edges b^3 , which extend to the edge of the ring and rest upon the beveled edge of the inner rim a^3 of the groove. By means of this metal ring the seat sections are continuously supported along both rims of the groove and also, at intervals, upon the cross partitions. It is thought that there is more danger of infection at the inner than at the outer edge of the seat and on this account the wooden seat sections are formed with the beveled inner edges in order that there 110

may be no sharp inner corners along this line and no flat horizontal surfaces to afford lodgment for infectious matter. It is therefore not only easier to clean along this edge but easier to keep clean by reason of these bevelled edges.

As shown in Fig. 1, the seat is provided at its rear with a double hinge or universal joint that admits of its front end being raised sufficiently to permit of the seat being rolled over sidewise. To this end a pivot pin D is secured to the seat and is mounted in a bearing socket e, in a cross bar E, which has end trunnions e¹, mounted in bearing brackets F, supported on the bowl extension A¹.

To reverse the seat, its front end is raised by rocking on the trunnions e¹ sufficiently to permit of its being turned over sidewise on its pivot pin D and then lowered, with that side which was the top now in under and lying in the sterilizing groove a. A handle G may be used conveniently in this operation. In order to afford points of support for this handle the metal ring C (see Fig. 5) has an extension c⁴ which projects at the front beyond the wood sections and may be provided with half round bars c⁵ secured upon each side. A similar extension c⁶ is formed at the rear of the metal ring for the attachment of the base g of the pivot pin D.

In Fig. 7 is shown a modification of the means for supporting the seat, which consists of a compass yoke or fork H, having a pivot pin D mounted in a pivoted cross bar E as in Fig. 2 and having its prongs h extend around to the sides of the seat, where they are apertured to form bearings h¹ for pivot pins J attached to the seat as shown.

These pins are preferably constructed as shown in Fig. 8, having splits j which may embrace the sides of the metallic ring under the wood sections and be riveted thereto. The pins also have flanges j¹ and trunnions j² with extensions j³ upon which suitable knobs or handles j⁴ may be secured. With this construction of the supporting devices the seat may be reversed or turned over in both directions that is either lengthwise on the pivot pins J or sidewise on the pivot pin D as will doubtless be readily understood by those skilled in the art to which this invention pertains.

While it has hereinbefore been described that the groove to contain the anti-septic material is formed in the top edge of the bowl it is not intended that it shall be understood that this is an essential feature of the invention because this groove may be made in the form of a separate trough or otherwise and suitably attached to the bowl. And further, while the described construction of the seat embodies the reinforcing metallic ring, this is considered as convenient and good construction but is not essen-

tial and the ring may be dispensed with if desired. And further, the partition walls across the groove may be omitted and the seat otherwise supported, in whole or part, without departure from the really essential features of the invention.

Having thus described the invention what is claimed as new and useful is:

1. A reversible toilet-closet seat having usable faces on both sides, a closet bowl and a receptacle at the top of the bowl adapted to hold anti-septic material and to receive the under face of the seat, with means for supporting the seat, whereby it may be turned over and guided into said receptacle.

2. A reversible toilet-closet seat having usable faces on both sides, a closet bowl and a receptacle at the top of the bowl adapted to hold anti-septic material and to receive the under face of the seat, annular flanged projections around both edges of the seat adapted to rest upon the respective rims of said receptacle, with means for supporting the seat in such manner that it may be turned over and guided into said receptacle.

3. A reversible toilet-closet seat having usable faces on both sides, a closet bowl and a receptacle near its top adapted to hold anti-septic material and to receive the under face of the seat, with a universal guide and hinge support at the back of the seat comprising a longitudinal pivot pin mounted in a cross bar which is pivotally mounted on supports at its ends the axial alinement of which is at a right angle to that of the pivot pin, whereby the seat may be rocked vertically on the axis of said cross bar and be turned over on the axis of the pivot pin.

4. A reversible toilet-closet seat having usable faces on both sides, a closet bowl and a receptacle adapted to hold anti-septic material and to receive the under face of the seat, with a guide and hinge support for the seat comprising a compass yoke extending from the rear around to the sides of the seat, pivot pins on the sides of the seat pivotally mounted in the forks of said yoke, a longitudinal pivot pin on the yoke in rear of the seat, a cross bar in which said pin is mounted and which is pivotally mounted at its ends in supports the axial alinement of which lies at a right angle to that of the last-mentioned pivot pin and parallel to that of the side pivot pins on the seat, whereby the seat may be rocked vertically on the axis of the cross bar and turned completely over, end for end, on the side pivot pins or turned over sidewise on the rear pivot pin.

5. In a reversible toilet-closet seat having usable faces on both sides and adapted to be turned over to bring either side up for use, a flat metallic ring with wooden seat faces secured to each side.

6. In a reversible toilet-closet seat having usable faces on both sides and adapted to

- be turned over, a toilet bowl having a grooved upper edge adapted to receive the under face of the seat, a flat metallic ring with wooden seat faces secured to each side, 5 the ring being wider than the seat faces its projecting edges adapted to rest upon the side rims of said groove.
7. In a reversible toilet-closet seat having usable faces on both sides and adapted to 10 be turned over to bring either side up for use, a toilet bowl having an annular groove in its top edge with partitions across the groove at suitable intervals, a flat metallic ring having a wooden seat face secured upon 15 each side the lowest face adapted to lie in said groove, said seat faces being composed of longitudinal sections which are spaced apart at intervals corresponding to the positions of the cross partitions in said groove, 20 said partitions standing in the spaces of the lower seat face and in supporting contact with the metallic ring where it crosses said spaces.
8. In a reversible toilet-closet seat having 25 usable faces on both sides and adapted to be turned over to bring either side up for use, a toilet bowl having an annular groove in its top edge with cross partitions at intervals, a flat metallic ring having a wooden 30 seat face secured upon each side, the lower
- face adapted to lie in said groove, said seat faces being composed of longitudinal sections which are spaced apart at intervals corresponding to the positions of the cross partitions of the groove which partitions 35 stand in the spaces of the lower seat face, said metallic ring being wider than the seat faces and resting at its projecting edges upon the rims of the groove and at said spaces upon the tops of the partitions. 40
9. In a reversible toilet-closet seat having usable faces on both sides and adapted to be turned over to bring either side up for use, a toilet bowl having an annular groove in its top edge the outer rim of which is flat 45 and the inner rim beveled on the groove side, a flat metallic ring between and wider than the seat faces and resting at its outer projecting edge on the flat outer rim while on the inner side the seat faces have beveled 50 edges which extend to the edge of the metallic ring and rest upon the beveled face of the inner rim for the groove.

In testimony whereof I have signed my name to this specification.

ROBERT DIAMOND MAYO.
